UNITED STATES PATENT OFFICE.

ALONZO A. WARNER, OF NEW BRITAIN, CONNECTICUT, ASSIGNOR TO LANDERS, EBARY & CLARK, OF NEW BRITAIN, CONNECTICUT, A CORPORATION OF CONNECTICUT.

QUICK-DETACHABLE CONNECTION FOR VACUUM-CLEANER NOZZLES AND THE LIKE.

Application filed January 15, 1923. Serial No. 612,808.

To all whom it may concern:

Be it known that I, ALONZO A. WARNER, a citizen of the United States, and a resident of New Britain, county of Hartford, and State of Connecticut, have invented certain new and useful Improvements in Quick-Detachable Connections for Vacuum-Cleaner Nozzles and the like, of which the following is a specification.

This invention relates to vacuum cleaners, and has particular reference to quick-detachable connections between the parts forming the air passage of the cleaner, for instance, between the nozzle and the fan casing, or between the dust bag and the casing. The aim of the invention is to provide connections of this sort having various features of novelty and advantage, and which are particularly characterized by the ease and facility with which the parts may be detached and secured together, and by the security and tightness with which the parts when connected are held together, the joint therebetween being, to all intents and purposes, fluid-tight.

My improved connection is extremely simple and economic in manufacture, efficient in operation, and presents a very neat and pleasing appearance.

In the accompanying drawing wherein I have shown, for illustrative purposes, one embodiment which the present invention may take,

Figure 1 is an assembly view in side elevation of an electric vacuum cleaner with its nozzle and dust bag attached to the fan casing by means of quick detachable connections constructed in accordance with the present invention;

Fig. 2 is a top plan view of the connection between the nozzle and casing;

Fig. 3 is a central longitudinal section through the parts shown in Fig. 2, being taken substantially on line 3-3 of said figure, and

Fig. 4 is a perspective view showing the parts, illustrated in Fig. 2, disconnected.

Referring to the drawings in detail, 10 designates the body portion of the electric vacuum cleaner mounted on casters 11, the body portion, as is usual, constituting a casing in which are housed a fan and an electric motor for driving the same. 12 is a suction nozzle connected to a tubular ex-

tension 13 constituting the inlet of the casing. The numeral 14 denotes the dust bag secured at its mouth to a sleeve 15 which is connected in telescopic relation to a tubular extension 16 constituting the outlet of the fan chamber or casing. It is understood, of course, that the cleaner shown in the drawing is illustrated by way of exemplification only.

In accordance with the present invention the suction nozzle 12 is provided with a tubular portion 20 adapted to telescope into the inlet extension 13, and having a shoulder 21 adapted to closely abut the shoulder 22 constituting the end surface of the extension 13. The external diameter of the portion 20 adjacent the shoulder 21, is preferably substantially the same as the internal diameter of the extension 13, but for the rest of its length it is of less diameter. In the present illustrative disclosure the internal diameter of the inlet extension 13 is uniform while the portion 20 is slightly tapered down towards its inner end. The tubular portion of the nozzle is preferably provided with a longitudinally extending key or rib 23 adapted to be slipped into a notch or slot 24 in the extension 13, when the parts are brought together. Projecting radially from the wall of the tubular portion 20 is a threaded member or stud 25 which, for instance, may be in the form of a screw positioned in a radial opening at the inner end of a key 23. The numeral 26 denotes a securing member which is here shown as being in the form of a nut threaded onto the projecting end of the screw 25, and preferably having its inner end tapered or conical, as indicated at 27.

Adjacent the inner end of the slot or notch 24 and preferably at each side thereof is an inclined surface 30 facing towards the fan casing and against these surfaces the conical end 27 of the nut engages, when screwed home, so that there is such a cam action therebetween that the tubular portion 20 is drawn into the inlet extension until the shoulders 21 and 22 are in close abutting relation. In the present example, these surfaces are formed by counterboring the inner end of the slot. This counterbore is slightly elongated, the surfaces 30 being struck about an axis slightly in advance of that from which the remaining surface 31 of the

counterbore is struck, so that the nut when engaging the surfaces 30 will be clear of the surface 31.

Upon screwing the nut down upon the 5 cam surfaces a force is set up which pulls the portion 20 of the nozzle into the inlet extension, and at the same time tends to draw together those walls of the telescoping members adjacent the securing means; that 10 is to say, there is an action which tends to rock the inner member (portion 20) relative to the outer one (extension 13) about a fulcrum adjacent the shoulders 21, 22. It will thus be seen that with the construction 15 described, to secure the parts together it is merely necessary to telescope the portion 20 into the extension and then screw the nut home, the shoulders thereby being brought into close abutting relation to form a substantially fluid-tight joint. The connection 20 may be very quickly and easily made, always with the assurance that a close joint will be formed between the shoulders.

The connection between the sleeve 15 of 25 the dust bag and the outlet extension 16 is similar in construction and operation to that of the nozzle and inlet connection, and therefore requires no further description.

It is, of course, obvious that the invention 30 is susceptible of various modifications and changes which are within the spirit of the invention without departing from the scope of the following claims, it being understood that the present disclosure is by way 35 of illustration only and it is not to be taken as restrictive of my conception.

What I claims is:—

1. In a device of the character described for use in connection with vacuum cleaners 40 and the like, a pair of telescoping members having shoulders adapted for abutting relation, and securing means therefor adapted to rock one member with respect to the other and thereby draw said shoulders into close 45 abutting relation.

2. In a device of the character described for use in connection with vacuum cleaners and the like, a pair of telescoping members having shoulders adapted for abutting relation, and securing means at one side of said 50 members arranged to relatively move said members longitudinally and relatively rock them and thereby draw said shoulders into close abutting relation.

3. In a device of the character described for use in connection with vacuum cleaners and the like, a pair of telescoping members having shoulders adapted for abutting relation, and a single securing means at one 60 side of said members arranged to longitudinally move and simultaneously rock one of said members with respect to the other and thereby draw said shoulders into close abutting relation.

4. In a device of the character described

for use in connection with vacuum cleaners and the like, a pair of telescoping members having shoulders adapted for abutting relation, said members being relatively fulcrumed adjacent said shoulders, and means 70 at one side of said members for securing said members together with said shoulders in close abutting relation.

5. In a device of the character described for use in connection with vacuum cleaners 75 and the like, a pair of telescoping members having shoulders adapted for abutting relation, the inner member adjacent said shoulders closely fitting within the outer member, and the inner member being tapered down 80 towards the inner end, and means at one side of said members for urging said inner member into the outer one and bringing said shoulders into close abutting relation.

6. In a device of the character described 85 for use in connection with vacuum cleaners and the like, a pair of telescoping members having shoulders adapted for abutting relation, and securing means arranged to exert a force longitudinally and a force radially 90 of said members to draw said shoulders into close abutting relation.

7. In a device of the character described for use in connection with vacuum cleaners 95 and the like, a pair of telescoping members having shoulders adapted for abutting relation, a cam surface provided on one of said members, and means carried by but movable relative to the other of said members and operable against said cam surface to urge 100 one of the members into the other and relatively rock said members.

8. In a device of the character described for use in connection with vacuum cleaners and the like, a pair of telescoping members 105 having shoulders adapted for abutting relation, the external diameter of the inner member being less than the internal diameter of the outer one, and means between said members and arranged at one side thereof 110 to draw said shoulders into close abutting relation.

9. In a device of the character described for use in connection with vacuum cleaners and the like, a pair of telescoping members 115 having abutting shoulders, a cam surface on the side of one of said members, and a securing member supported for radial movement by the other of said members and acting against said cam surface.

10. In a device of the character described for use in connection with vacuum cleaners and the like, a pair of tubular telescoping members having abutting shoulders, a cam surface on the side of the outer member and facing away from said shoulders, and a nut carried by the inner member and adapted 125 for engagement with said cam surface.

11. In a device of the character described, 130 a pair of telescoping members having shoul-

ders adapted for abutting relation, a stud on the inner member, the outer member having a longitudinal slot adapted to receive said stud and a cam surface facing away from the shoulders, and a nut carried by said stud adapted to engage against said cam surface.

12. In a device of the character described, a pair of telescoping members having shoulders adapted for abutting relation, a stud projecting radially from the inner member, the outer member having a longitudinal slot adapted to receive said stud, and cam surfaces at the sides of said slot, the inner member being slightly tapered, and a nut

having a conical end adapted to bear against said cam surfaces.

13. In a device of the character described, a pair of telescoping members having shoulders adapted for abutting relation, a stud projecting radially from the inner member, the outer member having a longitudinal slot adapted to receive said stud, and cam surfaces at the sides of said slot, the inner member being slightly tapered, a nut having a conical end adapted to bear against said cam surfaces, and a key on the inner member adapted to engage in said slot.

ALONZO A. WARNER.
